UNITED STATES PATENT OFFICE.

NATHAN M. LOWER, OF PITTSBURGH, PENNSYLVANIA, ASSIGNOR, BY MESNE ASSIGNMENTS, TO THE STANDARD STOKER COMPANY INC., OF NEW YORK, N. Y., A CORPORATION OF DELAWARE.

LOCOMOTIVE.

Application filed July 19, 1926. Serial No. 123,441.

The invention relates to locomotives, and particularly to improvements in the fire-boxes thereof, its object being to provide improved means for the introduction of fuel 5 into the fire-box, particularly when a power actuated stoker is employed.

The invention consists in a locomotive having a wall of its fire-box offset inwardly, the offset enclosing a chamber through which 10 the fuel may be introduced.

Preferred forms of the invention are disclosed in the accompanying drawings, in which—

Fig. 1 is a detail inside elevation of the rear 15 wall or back-head of a locomotive fire-box;

Fig. 2 is a detail section on the line 2—2 of Fig. 1;

Fig. 3 is a detail section on the line 3—3 of Fig. 2;

Fig. 4 is a view similar to Fig. 2, showing 20 a slightly modified form of construction;

Fig. 5 is a detail outside elevation of a back-head of the fire-box;

Fig. 6 is a sectional detail on the line 6—6 25 of Fig. 5;

Fig. 7 is a sectional detail on the line 7—7 of Fig. 6; and

Fig. 8 is a view in perspective of a distorted 30 ring incorporated into the back-head and partly surrounding the firing door opening and bounding the upper margin of the offset portion of the back-head.

In the construction of locomotive boilers it is the practice to form the walls of the fire-box as water legs, the chambers of which are 35 in communication with and form portions of the boiler. The lower ends of these water legs are closed by a heavy continuous metal structure known in the art as the mud ring.

The rear wall of the fire-box, commonly 40 called the back-head, is usually inclined somewhat in its upper portion, and its lower portion may be vertical. With these details, however, the present invention is not, broadly 45ly considered, concerned.

In the accompanying drawings the back-head is designated by the numeral 10, the interior of the fire-box being marked 11. The back-head is provided with the usual hand firing door opening, 12, to which any suitable form of closure, (none being shown) 50 may be applied. The mud ring is shown and indicated at 13.

In carrying out the invention that portion 55 of the back-head 10 which is immediately be-

low the door opening 12 is offset inwardly, as shown at 14. For the purpose of securing adequate strength the top and sides of the door opening 12 are bounded by a heavy metal ring 15, which is fitted between and tightly 60 secured by any suitable means to the inner and outer sheets 16—17, of the back-head. The bottom portion of the ring 15 is offset inwardly, as shown at 18 and forms the upper margin of the inset portion 14 of the back-head, being located between the portions 65 19—20 of the inner and outer sheets of the back-head which are inwardly offset.

Preferably the offset portion of the back-head is inclined downwardly and backwardly, its lower end being either somewhat forward of the main portion of the back-head, as indicated in Figs. 2 and 4, or may merge into the same plane as shown in Fig. 6.

A cover plate 21 is applied to the outer 70 face of the back-head, forming an outer wall or closure for the chamber 22 which is enclosed within the inwardly offset portion of the latter. Preferably the plate 21 extends above the hand firing door opening 12 and is 75 apertured as indicated at 23 in register therewith.

Any suitable means may be provided for the introduction of fuel into the fire-box through the chamber 22. As shown, an aperture 24 is formed in the plate 21 to give access 80 to this chamber.

The mud ring 13 may be distorted from 85 common practice to conform to the contour of the lower margin of the offset 14 of the back-head. This distortion may include the twisting of the ring in order that its outer and inward faces may be aligned with the portions 19—20 of the sheets which form the offset.

The upper margin of the offset portion 14 of the back-head may be horizontal, as shown in Fig. 4, or it may be downwardly and forwardly inclined, as shown plainly in Figs. 2 and 6. The latter form has the advantage of 90 providing for the free escape upwardly of any steam which may be generated within the offset portion of the back-head.

The invention provides a fuel feeding 95 chamber or passage leading to the interior of the fire-box, the inner walls of which are as effectually protected against the destructive action of the intense heat as are all other portions of the fire-box walls, and the grate area need not be encroached upon or mate- 100 110

rially reduced, even though it may be desired to increase the capacity of the feeding chamber or passage to a greater extent than is indicated in the drawings.

5. The described structure provides for the introduction of fuel into the fire-box by means of some form of force feed to and through the chamber inclosed by the offset section of the backhead, and for its scattering over the 10 grate by means such as a steam blast acting upon it as it issues from the chamber.

While preferred forms of construction are shown and described, other forms are available within the scope of the invention.

15. It is not of the essence of the invention in its broader aspects that the offset of the backhead be associated with the hand firing door opening. It may be entirely separate therefrom inasmuch as the purpose for which it is 20 intended is alternative to the main purpose for which the usual door opening is provided. In any case the offset section of the wall is open at the top for the passage of fuel into the fire-box.

25. Neither is the invention limited to the location of the offset at the bottom of the wall, nor in vertical median line of the backhead. Though the offset is shown as formed in the backhead, it may be in any other wall of the 30 fire-box through which it may be desired to introduce the fuel.

I claim as my invention—

1. A locomotive having a boiler and a firebox, a wall of the firebox being hollow and in 35 communication with the boiler, and having an inwardly offset section, the recess provided by said offset opening upwardly into the fire box.

2. A locomotive having a boiler, the backhead thereof having an inwardly offset section, the recess provided by such offset opening upwardly into the fire box.

3. A locomotive having a boiler, a section of the backhead on the vertical median line 45 thereof being inwardly offset, the recess provided by such offset opening upwardly into the firebox.

4. A locomotive having a boiler, the backhead thereof being provided with a hand firing opening, the section of the backhead immediately below such opening being inwardly offset, and a ring bounding the firing opening and the top margin of the offset.

5. A locomotive having in combination, a 55 boiler and a firebox, a wall of the firebox being hollow and in communication with the boiler and having an inwardly offset section,

the recess provided by such offset being upwardly open, and an apertured plate applied to the exterior of the wall and crossing the 60 recess provided by the offset section.

6. A locomotive having in combination, a boiler, the backhead thereof having an inwardly offset section, the recess provided by such offset opening upwardly into the firebox, and an apertured plate applied to the exterior of the backhead and crossing the 65 recess provided by the offset section.

7. A locomotive having, in combination, a boiler, the backhead thereof being provided 70 with a hand firing opening, the section of the backhead immediately below such opening being inwardly offset, and a plate applied to the exterior of the backhead and having apertures, respectively in register with the hand 75 firing opening and communicating with the recess provided by the offset section.

8. A locomotive boiler having a firebox, the rear wall of the box being hollow and provided with a hand firing opening, the section of the wall immediately below and defining the bottom of the named opening being offset inwardly, and means closing the upper margin of the offset section and being connected with the undistorted portion of the wall.

9. A locomotive having a boiler and a firebox, the backhead of the box being hollow and its chamber being in communication with the boiler chamber, a section of the lower portion of such backhead intermediate of its side margins being offset inwardly providing an external recess, such recess opening upwardly into the fire box, and a mud ring bounding the lower margin of the backhead and of its 95 offset section.

10. A locomotive having a boiler and a firebox, a wall of the boiler being offset inwardly to provide an exterior recess, such recess opening upwardly into the firebox.

11. A locomotive having a boiler and a firebox, the backwall of the firebox being hollow, its chamber communicating with the boiler, such wall being provided with a conventional hand firing opening, such opening being prolonged downwardly in the plane of the wall 100 to provide additional fuel opening to the firebox, and a hollow upstanding wall joining the margins of the prolongation of the hand firing opening and projecting into the firebox to provide a recess opening upwardly into the 105 firebox.

In testimony whereof I affix my signature.

NATHAN M. LOWER.
